MEANS FOR DE-ICING HANGAR DOOR TRACKS AND THE LIKE

Saul Saulson, Detroit, Mich., assignor to Albert Kahn, Inc., a corporation of Michigan

Application December 30, 1940, Serial No. 372,218

2 Claims. (Cl. 16—96)

This invention relates to track construction for hangar doors and the like including an inexpensive yet facile method and means for removing ice therefrom.

Both overhead door tracks and floor level door tracks become ice caked from driven rain and wet snow which freezes upon a sharp drop in temperature. Heretofore, various means have been employed to keep tracks for rolling doors free from ice in winter weather.

In hangar construction where door openings are extremely large, the doors are generally so heavy as to require them to roll on tracks at floor level rather than be suspended from trusses overhead. Prior to the instant invention, expensive grating covered pipe tunnel or trench construction has been employed under hangar door tracks wherein steam pipes melt snow and prevent ice from forming on tracks thereabove, and melt ice if formed on the hangar door tracks at times steam is not supplied to the steam pipes in the trench thereunder. The pipe tunnel or trench generally is sloped to a sump from whence water produced by melting the snow and ice is pumped. Heretofore, if the expensive tunnel or trench construction was not employed, a serious and continuous all-winter-long problem existed at hangars to keep the hangar door tracks clear of ice and snow whereby to permit the hangar doors to be opened and closed at all times. Where no de-icing provisions are made, salt or calcium chloride is generally employed to melt ice and snow at the hangar door tracks. However, the deleterious effect of such chemicals as salt and calcium chloride upon hangar door tracks and door wheels is undesirable. The expense of snow and ice removal from hangar door tracks at commercial hangars by crews of men has led to the employment of expensive steam heated trench or tunnel ice removal systems hereinbefore mentioned.

In military and naval hangars for fighting planes, it is of prime importance that the hangar door track always be kept free from ice and snow and that the door tracks and wheels be maintained free from rust or corrosion caused by employing chemical ice melting media.

With the foregoing in view, the primary object of this invention is to provide an efficient, inexpensive and positive method and means for maintaining hangar door tracks free from ice during sub-freezing weather.

Other objects of the invention will become apparent by reference to the following detailed de-

scription taken in connection with the accompanying drawing, in which:

Fig. 1 is a more or less diagrammatic plan view of one end of a hangar employing a track de-icing method and means embodying the invention.

Fig. 2 is a cross sectional view of the hangar door track taken on the line 2—2 of Fig. 1.

Fig. 3 is an enlarged fragmentary sectional view of a preferred type of hangar door track having a hangar door wheel indicated thereon.

Fig. 4 is a diagrammatic view of the method preferably employed to maintain the hangar door track above freezing temperature.

Fig. 5 is a fragmentary elevational view showing brine connections to the tubular portion of the hangar door track and the baffle employed to direct brine circulation therethrough.

Referring now to the drawing wherein like numerals refer to like and corresponding parts throughout the several views, the invention comprises, in general, one or more tracks 10 for hangar doors and the like, each track 10 composed of a tubular rail 11 preferably positioned in an upturned channel base 12 supported on a concrete foundation 13 capable of transferring uniformly the weight of one or more hangar doors from the track 10 to the ground 14 therebelow, a brine tank 15, a brine tank heater 16, and a brine pump 17 and suitable brine piping by means of which hot brine is pumped to and through the tubular rails 11 of the said hangar door tracks 10, all as hereinafter described in detail.

The hangar door tracks 10 each have the tubular rail 11 thereof fixed in the upturned channel base 12 by means of continuous welds 18 between the upper end of the channel flanges 120 and the sides of the said tubular rail 11. It will be noted that the said tubular rail 11 preferably bears on the center of the inside of the back 121 of the said upturned channel 12. Thus, two air spaces 19 are formed between the tubular rail 11 and the channel base 12 of the track 10 into which is entrapped air which serves as an insulation medium to minimize the heat loss between the tubular rail 11 of the track 10 and the foundation 13.

In the particular embodiment of the invention shown in the drawing, the two hangar door tracks 10 are preferably secured by welds 180 to transverse angle sleepers 20 which are embedded into the concrete foundation 13. Strap anchors 21 welded by welds 181 to the said angle sleepers 20 fix them securely into the concrete foundation 13. The construction of the concrete foundation

13 is much more simple and less expensive than the prior art grating covered trench and pipe tunnel construction and has the further advantage that it does not serve as a collecting place for dirt, paper, oil and mud, and frequent and expensive cleanings thereof are not necessary. The top of the rail 11 of each track 10 is preferably maintained at the level of the hangar floor 22 and the apron 23 so as to be of minimum obstruction to traffic thereacross. The concrete foundation 13 is grooved as indicated by the numeral 35 along each side of the upper half of the tubular rail 11 of each track 10 as best shown in Figs. 2 and 3. A suitable construction joint 24 is provided between the track foundation 13 and the hanger floor 22 and apron 23 to admit of expansion and settlement of each independent of the other.

Fig. 1 discloses more or less diagrammatically a hangar 25, the hangar floor 22, apron 23, door tracks 10, track foundation 13, and hangar walls 26 which are formed into door pockets 27 adjacent the hangar door opening into which hangar doors rolling on the tracks 10 are telescoped when the hangar doors are opened for the purpose of placing planes into or removing them from the hangar 25. The brine tank 15, brine pump 17, and the brine make-up and expansion tank 28 are all indicated diagrammatically in Fig. 1 and are preferably supported on a platform 29 suspended in the roof trusses of the hangar 25.

The brine and brine tank heater piping preferably employed is best indicated in Fig. 4 which shows diagrammatically in isometric perspective the brine tank 15, brine tank heater 16, brine pump 17, the brine make-up and expansion tank 28, and the tubular rails 11 of the hangar tracks 10. Brine or other anti-freeze mixture made up in the brine make-up and expansion tank 28 is first run by gravity into the brine tank 15, through the entire brine piping and into the brine pump 17 in the usual manner in which such a system is filled.

After the brine system is filled, steam is admitted through the steam supply line 30 to the brine heater 16 disposed in the brine tank 15 and spent steam is returned from the said brine heater 16 through the steam return line 31. Obviously, other means may be employed for heating the brine in the brine tank 15 such as an oil burner, gas burner or an electric immersion heater. Heated brine is supplied to the tubular rails 11 by means of the brine pump 17 and brine supply line 32, and the brine which circulates through the tubular rails 11 of the tracks 10 as indicated in Fig. 4 is returned to the brine tank 15 through the return brine line 33 by the brine pump 17 which is preferably disposed in the return brine line 33. A baffle 34 is disposed in the tubular rail 11 of the hangar door track 10 between the connections of the brine supply and return lines 32 and 33 thereto assuring positive circulation of hot brine through the tubular rails 11 of the hangar door tracks 10. When more than one hangar door track 10 is employed, it is preferable that the brine be directed to circulate through the outer rail first and through the inner rail second; this because all of the outer rail is exposed to the elements and only a portion of

the inner rail is exposed to the elements when the hangar doors are closed.

The instant invention has provided a simple, inexpensive and practical means for de-icing tracks of hangar doors and the like which employs but a small trough or groove 35 adjacent thereto which may be easily cleaned as compared to prior art pipe tunnel and trench construction which is not easily cleaned and becomes ineffective when filled or partially filled with water, snow, mud and the like. The employment of a heated rail 11 of hangar door track 10 quickly and effectively loosens snow and ice therefrom sufficiently to permit the wheels 36 of the hangar doors 37 to break any ice that may form on the rail 11 off therefrom as the said hangar doors 37 are rolled open or closed. The instant invention requires much less heat and fuel to operate than previous constructions, and the track cleaning crews necessitated during sub-freezing weather need only be a fraction of the size normally required to maintain hangar doors in free working condition.

In hangars for the air corps and naval bases, an auxiliary brine heating and pumping system may be employed to assure the de-icing of the hangar door tracks in the event the main brine heating and circulating system should fail.

Although but a single embodiment of the invention has been disclosed and described in detail, it is to be understood that many changes in the size, shape, arrangement and detail of the various parts thereof may be made and that the novel method employed to accomplish the desired results may be altered, all without departing from the spirit of the invention, and it is not intended to limit the scope of the invention other than by the terms of the appended claims.

I claim:

1. In de-icing means for door tracks for hangar doors and the like including means for circulating an anti-freeze medium through said rails, and means for heating said anti-freeze medium sufficiently to raise the temperature of the said rails above freezing; said track comprising one or more tubular rails, a foundation under said tracks, jacket means between the lower portion of each tubular rail and the said track foundation for minimizing heat loss between the said tubular rail and the said track foundation.

2. In de-icing means for door tracks for hangar doors and the like including means for circulating an anti-freeze medium through said rails, and means for heating said anti-freeze medium sufficiently to raise the temperature of the said rails above freezing; said track comprising one or more tubular rails, a foundation under said tracks, an up-turned channel supporting each rail embedded in the track foundation, the sides of each tubular rail being welded continuously to the upper end of the flanges of its supporting channel forming continuous air spaces along each said tubular rail between the rail and its supporting channel whereby to minimize heat loss between the said tubular rail and the track foundation.

SAUL SAULSON.
